CLAIM

The ornamental design for a sheet product dispenser, as shown and described.

DESCRIPTION

FIG. 1 is a top, front, and right side perspective view of a sheet product dispenser showing our new design;

FIG. 2 is a front elevational view thereof;

FIG. 3 is a top plan view thereof;

FIG. 4 is a bottom plan view thereof;

FIG. 5 is a left side elevational view thereof, the right side being a mirror image thereof; and,

FIG. 6 is a rear elevational view thereof.

The broken-line disclosure in the views is understood to represent portions of the article in which the claimed design is embodied, but which forms no part of the claimed design.
